UNITED STATES PATENT OFFICE.

CHARLES M. VERNON AND GEORGE VON VERNON, OF ZANESVILLE, OHIO.

COMPOSITION TO BE USED IN SWEEPING.

No. 873,913.

Specification of Letters Patent.

Patented Dec. 17, 1907.

Application filed July 5, 1907. Serial No. 382,363.

To all whom it may concern:

Be it known that we, CHARLES M. VERNON and GEORGE VON VERNON, citizens of the United States, residing, at Zanesville, in the county of Muskingum and State of Ohio, have invented a new and useful Composition of Matter to be Used for Controlling Dust, Polishing Floors, and Destroying Germs in Sweeping Floors, Carpets, &c., of which the following is a specification.

Our composition consists of the following ingredients, combined substantially in the following proportions, viz: oil meal, linseed, cottonseed, or both, three hundred pounds; clay, two hundred pounds; light neutral oil of $34\frac{1}{2}$ to $38\frac{1}{2}$ gravity, secured from petroleum oil, four hundred and fifty pounds; paraffin oil, three hundred and seventy five pounds; lubricating oil of $22\frac{1}{2}$ to $28\frac{1}{2}$ gravity, secured from petroleum oil, three hundred and seventy five pounds; sand, twelve hundred pounds; sawdust, nine hundred pounds; anilin cotton green, two pounds; sodium chlorid, (common salt), twelve pounds; and oil of mirbane, (nitrobenzene), three pounds. The proportions of these ingredients may be considerably varied, and one or more of said ingredients may be dispensed with as herein-after claimed, without substantially affecting the efficiency of the composition to do its work; and they are to be thoroughly mingled or mixed by agitation.

Oil meal is a natural and perfect oil absorbent, and may be used with its natural oil therein; but we prefer to use that which has its natural oil partially or completely extracted therefrom. Clay is an oil absorbent, and it also increases the specific gravity of the composition. All the oils control dust and polish floors; and the paraffin oil and the lubricating oil add a permanent quality of moistness to the composition which it must have to control dust; and the lubricating oil also adds to the floor-polishing quality of the composition. Sand absorbs some oil, and increases the specific gravity of the composition; and especially, it keeps the mass finely separated and suitable for use. Sawdust absorbs some oil, and especially, it adds bulk to the mass, which is very essential. Anilin cotton green gives the color, a bright green, which the sodium chlorid brings out or brightens, and also sets.

Oil of mirbane, or nitrobenzene, is a positive germicide and it also gives the odor to the composition.

We claim:

1. The herein described composition of matter, consisting of oil meal, clay, light neutral oil, paraffin oil, lubricating oil, sand, sawdust, anilin cotton green, sodium chlorid, (common salt), and oil of mirbane, (nitrobenzene), substantially as described and for the purposes specified.

2. The herein described composition of matter, consisting of oil meal, light neutral oil, sand and sawdust, substantially as described and for the purposes specified.

3. The herein described composition of matter, consisting of oil meal, sand, light neutral oil, paraffin oil and sawdust, substantially as described and for the purposes specified.

4. The herein described composition of matter, consisting of oil meal, sand, light neutral oil, lubricating oil and sawdust, substantially as described and for the purposes specified.

5. The herein described composition of matter consisting of oil meal, clay, sand, light neutral oil, paraffin oil, lubricating oil and sawdust, substantially as described and for the purposes specified.

6. The herein described composition of matter, consisting of oil meal, light neutral oil, sand, sawdust, anilin cotton green, sodium chlorid, (common salt), and oil of mirbane, (nitrobenzene), substantially as described and for the purposes specified.

7. The herein described composition of matter, consisting of oil meal, three hundred pounds; clay, two hundred pounds; light neutral oil, four hundred and fifty pounds; paraffin oil, three hundred and seventy five pounds; lubricating oil, three hundred and seventy five pounds; sand, twelve hundred pounds; sawdust, nine hundred pounds; anilin cotton green, two pounds; sodium chlorid, (common salt), twelve pounds; and oil of mirbane, (nitrobenzene), three pounds, substantially as described.

CHARLES M. VERNON.
GEORGE VON VERNON.
